(57) **CLAIM**

The ornamental design for a flask, as shown and described.

DESCRIPTION

FIG. 1 is a front view of a flask;
FIG. 2 is a rear view of the flask depicted in FIG. 1;
FIG. 3 is a top view of the flask depicted in FIG. 1;
FIG. 4 is a bottom view of the flask depicted in FIG. 1; and,
FIG. 5 is a perspective view of the flask depicted in FIG. 1.
The broken line showing of the top indicia, bottom contours,
and the draw tube components illustrate portions of the flask
that form no part of the claimed design.

1 Claim, 2 Drawing Sheets
